UNITED STATES PATENT OFFICE.

EDWARD READ, OF CAMBRIDGE, ASSIGNOR TO THE WILLIAM READ & SONS, OF BOSTON, MASSACHUSETTS.

DESIGN FOR A NAME-PLATE FOR BICYCLES.

SPECIFICATION forming part of Design No. 25,043, dated January 7, 1896.

Application filed December 2, 1895. Serial No. 570,859. Term of patent 3½ years.

To all whom it may concern:

Be it known that I, EDWARD READ, a citizen of the United States, residing at Cambridge, in the county of Middlesex, State of Massachusetts, have invented and produced a new and original Design for a Name-Plate for Bicycles, of which the following is a specification, reference being had to the accompanying drawings, showing the same.

Figure 1 is a front view of a name-plate, showing my design. Fig. 2 is a side elevation of the same, and Fig. 3 is a plan, these three views being deemed necessary to fully illustrate my design.

The leading feature of my design consists in a straight bar with three pairs of laterally-projecting curved arms.

In the accompanying drawings, 2 is a straight flat bar rectangular in cross-section and serves as the center piece which is to set in an upright position. Laterally on each

side are three pairs of arms 3. These arms are rectangular in cross - section and are curved or circular in plan view, as shown in Fig. 3. Said arms are furthermore bent, as shown in Figs. 1 and 2, curving downwardly from their point of union with the center piece to a point about midway of their length and then gradually rising and tapering to a point 4, which is on a level with the upper edge of the arm at its junction with the center piece. In side elevation these arms present the general appearance of a horn, while the central end portions of the name-plate are tipped with circular apertured disks 5.

35

What I claim is—

The design for a name plate for bicycles as set forth.

EDWARD READ.
